Inventor:

Q. S. Anderson

Leopold von Sacher-Masoch

UNITED STATES PATENT OFFICE.

ROBERT SCOTT ANDERSON, OF TORONTO, CANADA.

BICYCLE-MOTOR.

SPECIFICATION forming part of Letters Patent No. 710,881, dated October 7, 1902.

Application filed April 4, 1901. Serial No. 54,339. (No model.)

To all whom it may concern:

Be it known that I, ROBERT SCOTT ANDERSON, of the city of Toronto, in the county of York, in the Province of Ontario, Canada, 5 have invented certain new and useful Improvements in Bicycle-Motors, of which the following is a specification.

My invention relates to improvements in bicycle-motors; and the object of the invention is to devise a form of motor readily adaptable to a bicycle which will be simple, compact, and easily operated. To carry out these objects my invention is constructed and arranged in detail, as hereinafter more 15 particularly explained, reference being had to the accompanying drawings, in which—

Figure 1 is a horizontal section through the engine, main shaft, and fly - wheel casing. Fig. 2 is a sectional elevation.

20 A is the front standard of the bicycle. B is the rear standard, and C the rear forks.

F is the fly-wheel casing, which is made in two parts suitably connected together in the center of the periphery by the lugs f and 25 bolts f' extending therethrough.

f² is a plate attached to or forming part of the casing F at the front thereof.

G is the cylinder of the engine, which at the lower end is provided with a flange g, 30 by which it is secured to the plate f².

G' is the head of the cylinder, which is suitably screwed onto the threaded outer end of the upper portion of the cylinder, as indicated in Fig. 3. The sleeve g' of the head 35 extends down over the major portion of the cylinder. Into the head G' extends at the front side the end of the exhaust-pipe 2. 4 is the inlet - pipe, which extends into the head G' of the cylinder diametrically opposite the exhaust-pipe 2. The upper end of 40 the head G' is provided with a socket g³, into which fits the lower end of the lower reach A.

G² is the piston, which is connected by the pins g² to the piston-rod g⁴, which has formed 45 at the outer end of it a ring g⁵, in which works the eccentric g⁶, attached to the hollow engine-shaft II. The hollow engine-shaft II extends through the sides of the casing, being journaled in suitable ball- bearings at the outer ends, as indicated.

I is the pedal-shaft, which extends into the engine-shaft and is journaled at the ends in suitable ball-bearings, the cones of which are situated within the cones of the bearings of the engine-shaft in the manner now de- 55 scribed.

h h are the cones of the engine-shaft, which are suitably screwed onto the end of the same. The balls h' h' are located between the cones h h and the outside cones h² h², held in 60 suitable annular flanges formed on the two sides of the casing F. The cones h h extend outwardly, so as to form outer cups h⁴ h⁴, between which and the cones h⁵ h⁵ on the pedal-shaft are located the balls h⁶. 65

H' is a sprocket-wheel having an opening extending therethrough internally threaded and fitting on the threaded end of the cone-bearing h at one end of the engine-shaft.

H² is a brake - wheel which is provided 70 with a central opening internally threaded and fitting onto the corresponding end of the double cone h at the opposite end of the shaft.

H³ is a sprocket-wheel secured onto the end 75 of the pedal-axle I, which is provided with the usual pedals i.

J J are the fly-wheels, which are suitably secured on the hollow engine-shaft, as indicated. 80

The eccentric g⁶, hereinbefore described, is secured on the hollow engine-shaft in the following manner: A hole g⁷ is made in the eccentric, which serves the double purpose of lightening as well as permitting the eccentric to be placed in position—that is to say, slipped over the annular flanges g⁸, attached to or forming part of the hollow engine-shaft. The eccentric is then secured in position by suitable pins g⁹. I may finally mention the 85 eccentric rotates on ball-bearings between it and the ring on the end of the piston-rod.

What I claim as my invention is—

1. The combination with the hollow engine-shaft suitably journaled in the casing 95 and provided with annular flanges and the cylinder and piston, of the eccentric having an opening therein and pins extending therethrough for securing it to the annular flanges and the piston-rod having a ring-shaped end 100

fitting over the eccentric and the opposite end suitably connected to the piston as and for the purpose specified.

2. The combination with the frame and 5 suitable bearings at the interior of the lower portion thereof, of the hollow engine-shaft suitably journaled in such bearings and the pedal-axle extending through the engine-

shaft and provided with suitable end bearings and suitable connecting driving means 10 between the pedal-axle and the engine-shaft as specified.

ROBERT SCOTT ANDERSON.
